UNITED STATES PATENT OFFICE.

JOHN A. BOYCE, OF SPRINGFIELD, ILLINOIS.

APPARATUS FOR PRINTING AND FOLDING PAPERS.

No. 900,654.

Specification of Letters Patent.

Patented Oct. 6, 1908.

Original application filed May 9, 1904, Serial No. 207,079. Divided and this application filed September 23, 1904.
Serial No. 225,644.

To all whom it may concern:

Be it known that I, JOHN A. BOYCE, a citizen of the Dominion of Canada, residing at Springfield, in the county of Sangamon and State of Illinois, have invented certain new and useful Improvements in Apparatus for Printing and Folding Papers, of which the following is such a full, clear, and exact description as will enable others skilled in the art to which it appertains to make and use my said invention.

This application is a division of my application No. 207,079, apparatus for printing and folding newspapers, filed May 9, 1904.

My invention relates to apparatuses such as are used to print and fold papers in book form.

The purpose of my invention is to produce an apparatus having continuously rotating and positively quick acting folder devices coöperating with a printing apparatus having plate cylinders carrying plates with columns lengthwise of said cylinders to always fold at the same speed and always fold in book form irrespective of the number of decks in use, and without using duplicate plates.

With this general purpose in view the more specific purposes are; to provide an apparatus in which the first folder cylinder and first folder rollers are parallel to and in direct line with the plate cylinders of the press thereby reducing to the minimum the travel of the webs and avoiding the use of complicated means for changing the direction of travel of the webs, and to provide simple and effective means for slitting the web and conveying the web-members to the folder devices.

With these ends in view my invention consists in the novel features of construction and combinations of parts shown in the annexed drawings to which reference is hereby made; and hereinafter particularly described, and finally recited in the claims.

Referring to the drawings, in which similar reference letters designate like parts in the several views; Figure 1.—is an end elevation of the apparatus. Fig. 2.—is a partial top plan. Fig. 3.—is an elevation of the left hand side of the apparatus. Fig. 4.—is an elevation of the right hand side of the apparatus. Fig. 5.—is a horizontal section on the line 5. 5. of Fig. 3.

In these views gear wheels are shown by

pitch circles, and other parts of the mechanism are shown in outline only.

The gist of the invention consists in the relative arrangement and relation of the parts, and it is therefore unnecessary to show and describe well known details of construction in which this apparatus does not materially differ from other apparatuses in common use.

The main frame A, is of the usual construction and is arranged to support multiple sets of rotating plate cylinders B, carrying plates lengthwise of the cylinder. Each of the plate cylinders B is two plates in circumference and preferably two or more plates in width. The main plate cylinders are equipped with exclusively original plates; duplicate plates being used only on the supplement plate cylinders. Paper rolls C, mounted in suitable bearings on the frame, supply web to the plate cylinders. Rotating blanket cylinders D, of the usual well known form coöperate with the plate cylinders. The printing apparatus may also have inking devices of any suitable form; but such inking devices form no part of my invention and therefore are not shown or described.

The means shown in the drawings for operating the plate cylinders and blanket cylinders of all of the decks at full speed consist of a vertical shaft D¹, turning in bearings on the main frame; bevel cog pinions D², secured on the shaft D¹, by set screws d; bevel cog pinions D³, secured on the shafts of the cylinders D and meshing with and driven by the pinions D²; and a bevel cog pinion D⁴, secured on the main drive shaft D⁵ and meshing with and driving the lower cog pinion on the shaft D¹. Intermeshing spur wheels B¹, secured on the shafts of the cylinders D, and B, cause them to turn in unison.

The means shown in the drawings for operating one set of blanket cylinders and plate cylinders at half speed consists of a vertical shaft D⁶, turning in bearings on the main frame; a bevel cog-wheel D⁷, secured on the shaft of one of the blanket cylinders; a bevel cog pinion D⁸, secured on the shaft D⁶, by a set-screw d¹, and meshing with the cog-wheel D⁷; a bevel cog pinion D⁹, secured on the shaft D⁶; and a bevel cog-wheel D¹⁰, secured on the main-drive shaft D⁵, and meshing with and driving the pinion D⁹.

When it is desired to operate the cylinders of the lower deck at half speed and the cylin-

ders of the other decks at full speed the set-screw d_1 of the pinion D^2 , which meshes with the pinion D^3 , of the lower deck, will be loosened, and the pinion D^2 , slid upward on the shaft to disengage it from the pinion D^3 , and secured in that position. The pinion D^8 , will then be secured in mesh with the pinion D^7 , and the turning of the main drive-shaft D^6 , will cause the shaft D^6 , to drive the cylinders of the lower deck at half-speed, and the shaft D^1 , to drive the cylinders of the upper and middle decks at full speed. When it is desired to drive all of the plate cylinders at full speed it is only necessary to disengage the pinion D^8 , and engage all of the pinions D^2 with the corresponding pinions D^3 . Any other suitable means may be employed to operate one deck at half-speed and one or more decks at full-speed, without departing from my invention.

A folder cylinder E turns in suitable bearings on the main frame parallel to the plate cylinders and is geared to revolve at one half the speed of the plate cylinders. The folder cylinder E , which is one half the length of and twice the diameter of the plate cylinders B , has two internal diametrically opposite revolving blades which alternately act through slits in the wall of the cylinder to crease the sheets running on the folder cylinder and project the creased sheets into position to be seized and operated upon by the folder rollers H substantially as shown and described in my said application No. 207079.

First-cutter cylinders F , which are of the same diameter and one half the length of the plate cylinders, are actuated by suitable gearing to turn in unison in bearings on the main frame at the same speed as the plate cylinders and are equipped with a longitudinal blade f and a corresponding longitudinal cutting-wood f' which serve to cut into sheets two-pages in length the webs delivered by the former to said cutter cylinders as hereinafter described.

The plate cylinders B , and the blanket cylinders D , on one of the decks are geared so that they may be operated at half the speed of the like parts of the other deck or decks; and the plate cylinders and the blanket cylinders of the other deck or decks turn in unison with the main cutter cylinders as already explained.

Upper and lower supplement cutter cylinders G of half the length and half the diameter of the plate cylinders, are in line with and turn in unison with the half speed plate cylinders and the upper cylinder has a blade g and the lower cylinder has a corresponding cutting wood g' which coöperate to cut the half web used on the coöperating plate cylinders into sheets one page in length, which are delivered by suitable means (not shown) on to the surface of the cylinder E , and are carried around on the cylinder and delivered

to the first folder rollers H , by which they are folded between the two page sheets delivered to the folder cylinder from the cutter cylinders F . Folder rollers H , geared to co-operate with the rotating blades e in the folder cylinder E , turn in suitable bearings on the main frame and seize and fold the sheets as delivered to the folder rollers from the cylinder E . The folder cylinder E , is driven by a shaft E^1 , which turns in suitable bearings on the main frame and has a bevel cog wheel E^2 , which meshes with and drives a similar cog pinion E^3 , secured on the shaft of the folder cylinder E . A cog wheel E^4 , secured on the other end of the shaft E^1 , meshes with and is driven by a cog-pinion E^5 , secured on the main-drive shaft D^6 . The train of gear wheels is such that the folder cylinder revolves in the proper direction at the same speed as the plate cylinders. Any other suitable means may be employed for operatively connecting the folder cylinder with the plate cylinders, without departing from my invention. A suitable train of gear wheels connects the folder cylinder E , with the main cutter cylinders F , the supplement cutter cylinders G and the folder rollers H so that all will coöperate in due time as described.

A series of angle bars K , corresponding in number and arrangement to the sets of plate cylinders B , are mounted on and extend diagonally across the main frame above the former M . The former M , which is of the usual well known construction is mounted on the main frame. The lower edge of the former is contiguous and parallel to the main cutter cylinders and its upper edge is at right angles to its lower edge. The former is plural-plates-wide in its large dimension,—the upper edge—and one plate wide in its smaller dimension—the lower edge—and serves to associate the web-members in book form in line with the supplement sheets. The part of the former in which the converging edges unite is for convenience of description hereinafter designated as the nose of the former.

The angle bars K and the former M together constitute an associating device which serves to associate all of the web-members of a single web in book form and present them to the main cutter cylinders, by which they are cut into sheets in length equal to the width of two pages plus margins; and in a multiple-deck apparatus all of the webs travel over a single former and the former in addition to associating the web-members serves to bring together or consolidate the several webs with the pages in book form and present the associated and consolidated webs to the main cutter cylinders by which they are cut into sheets in length equal to the width of two pages plus margins.

A series of rotating rollers N , correspond-

ing to the angle bars K in number and position are geared to support and propel the webs at the proper speed, in their travel between the angle bars and the former. Adjustable slitter knives N¹, of the usual construction mounted on shafts N² parallel to the rollers N, slit the webs longitudinally as they travel on the rollers N. The shafts N², also support rubber-faced wheels N³ which serve to hold the paper webs in close contact with the surface of the rollers N. A loose roller P, and an adjustable pipe roller R, of the usual well known form, are mounted to turn in bearings on the main frame. Suitably geared rollers S, near the lower end of the former pull on the overlapped web-members as they leave the lower end of the former and lead them to the main cutter cylinders F. Suitably geared rollers T, provided with tapes T¹, serve to convey the folded papers away from the first-folder rollers H.

The second folder device is preferably of the form shown and described in my said application 207079 but a second-folder device of any other suitable construction may be used without departing from my invention. The second-folder device in its preferable form consists of a rapidly rotating folder blade W, mounted on radial arms W¹, which are secured on and turn with the shaft W², at right angles to the first folder cylinder. The shaft W², turns at the proper speed to cause the folder blade to strike the paper at the instant that the center of the paper is adjacent to the second folder rollers W³, which are geared and speeded to seize the papers as they are creased and projected downward by the blade W, and pass them between the rollers there-by making the second fold transverse to the first fold. The folded papers may then be counted and conveyed away by any suitable means.

The three deck apparatus shown in the drawings is adapted to produce a paper of twenty-four pages in book form when all of the plate cylinders are operated at full-speed with full complements of plates. By increasing the number of decks in the press the production may be correspondingly increased without changing the folder mechanism, that is to say; an apparatus employing a four-deck press will produce thirty-two pages in book form; five decks will produce forty pages in book form; and so on according to the number of decks used.

In producing a paper with a supplement or insert-sheet one of the decks is operated at half speed with a half complement of plates using a half width web; and the other deck or decks are operated at full-speed with a full complement of plates and using full width web.

The operation of the apparatus is as follows; To produce a twenty-four page paper

in book form without supplement; full width webs will be used on all of the decks; all of the plate cylinders will operate at full-speed and carry a full complement of plates. In that case all of the webs from the plate cylinders will be threaded to pass up around the angle bars K; thence to the rollers N, upon which they will be slit longitudinally by the slitter devices N¹, to divide each of the webs into two web-members; the web-members will then pass around the roller P and under the roller R, to the former M; thence downward along the former to its lower edge where the web-members will be overlapped, and led by the rollers S, to the main cutter cylinders F, by which they will be cut into sheets two pages in length; and will be stripped from the lower (female) cylinder F by strippers f² and led downward on the surface of the cylinder E by a rotating brush f³ or equivalent leading device until the margin between the pages of the cut sheets is parallel and contiguous to the first folder rollers H; when in this position, the revolving blades mounted in the folder cylinder, will alternately operate to thrust the sheets outward into position to be caught and folded by the folder rollers H; from which the folded sheets will be conveyed away by tapes T¹, or other suitable conveying devices into position to be operated upon by the second folder device. The second folder devices will then make the second fold transverse to the first, as already described.

If 8 pages in book form is desired, it will be necessary to operate only one set of plate cylinders at full speed with a full complement of plates. To produce 16 pages in book form two sets of plate cylinders operating at full speed with full complements of plates will be used. To produce 10 pages in book form, one deck of the printing mechanism (preferably the lower) will be operated at half speed, with a half width web and a half-complement of plates and one of the other decks (it does not matter which one,) will be operated at full speed with a full complement of plates and full-width web. The web from the full-speed plate cylinders will then be threaded, slit and cut into sheets as already described.

The half width web from the half-speed plate cylinders will pass directly to the supplement cutter cylinders G, by which it will be cut into sheets one-page in length and said sheets will be led by tapes g² or equivalent leading devices around and next to the outer surface of the folder cylinder E. The supplement cutter cylinders are adjacent and parallel to the first folder cylinder and between the folder cylinder and the half-speed printing couples, and the half-speed web travels in a straight line, directly between the supplement cutter cylinders and the cut sheets are delivered on-to the adjacent quarter of the

4
5 folder cylinder which is turning towards the main cutter cylinders; thereby avoiding any circuitous travel of the supplement web on sheets and obviating the use of long tapes to 10 convey the supplement sheets to the folder cylinder. This operation will be so timed that one page of each of the two-page sheets will over lie the supplement sheet carried on the surface of the folder cylinder.

10 15 When the margin between the pages of the two-page sheets reaches a position adjacent and parallel to the folder rollers II, the rotating blades within the folder cylinder will act to crease the double sheets and project them outward into position to be caught and folded by the folder rollers and the supplement sheet will lie between the inside pages of the double sheet.

15 20 The means for actuating the plate cylinders, the pipe rollers, the slitter devices, the cutter cylinders, the folder cylinders and the folder rollers may be of any suitable or convenient construction and are therefore not shown in detail nor particularly described.

20 25 I am the first to organize an apparatus comprising full speed plate cylinders always two plates in circumference and having columns lengthwise of the plate cylinders and always equipped with original plates exclusively;

25 30 half-speed plate cylinders always two plates in circumference and equipped with both original plates and duplicate plates, with columns lengthwise of the plate cylinders; a folder cylinder one-plate-wide in

30 35 line with and coöperating with the full-speed plate cylinders and the half-speed plate cylinders and a turner device and associating device so arranged that the web members and the sheets cut therefrom always have a continuous straight run without retardation

35 40 cross travel or backward travel, and are always associated and folded in book form; without the use of duplicate plates on the full speed main plate cylinders; and the final delivery of the folded papers is always commensurate to the capacity of the full speed-plate-cylinders.

40 45 Having fully described my invention what I claim as new and desire to secure by Letters Patent is;

45 50 1. In an apparatus of the class described, the combination of full-speed rotary plate cylinders equipped with exclusively original plates with columns lengthwise of the plate cylinders, coöperating blanket cylinders, a rotary first folder cylinder parallel to the plate cylinders, means for leading invariably toward the folder cylinder and always in parallel and associating in book form all the members of a single web, main cutter cylinders cutting independently of the folder cylinder and adapted to cut the full-speed web members into sheets in length equal to the width of two pages plus margins and always 55 60 65 cutting off a complete paper exclusive of

supplement for each revolution of the plate cylinders, half-speed supplement printing couples printing said supplement web, rotary supplement cutter cylinders cutting the supplement web into sheets one page in length and delivering same on the quarter of the folder cylinder approaching the female main cutter cylinder and rotary folder rollers contiguous to said first folder cylinder; all coöperating to produce a complete paper in book form with supplement for each and every revolution of the full speed plate cylinders.

2. In an apparatus of the class described, the combination of rotary plate cylinders carrying plates with columns lengthwise of said plate cylinders, coöperating blanket cylinders, a rotary folder cylinder parallel to said plate cylinders, main cutter cylinders adjacent and parallel to said folder cylinder and cutting independently thereof and always cutting off a complete paper exclusive of supplement, for each revolution of the plate cylinders, supplement cutter cylinders between said folder cylinder and said plate cylinders, rotary folder rollers adjacent to said folder cylinder and a former in operative relation to said plate cylinders and first cutter cylinders, as set forth.

3. In a multiple deck apparatus of the class described, the combination of multiple sets of full-speed plate cylinders carrying exclusively original plates with columns lengthwise of said plate cylinders, multiple sets of coöperating blanket cylinders, a rotary folder cylinder parallel to and turning in unison with the full speed plate cylinders, half-speed supplement printing couples, rotary supplement cutter cylinders adjacent to and cutting independently of the folder cylinder and in line with and between the folder cylinder and the half-speed plate cylinders, an associating device in operative relation to the full-speed plate cylinders and adapted to lead always in parallel and invariably toward the folder cylinder all of the web members from all of the full-speed plate cylinders, main cutter cylinders in operative relation to said associating device and adapted to cut the associated full speed web members into sheets in length equal to the width of two pages plus margins and cutting off a complete paper exclusive of supplement for each and every revolution of the full-speed plate cylinders.

4. In a multiple deck apparatus of the class described, the combination of multiple sets of plate cylinders carrying plates with columns lengthwise of said plate cylinders, multiple sets of coöperating blanket cylinders, a rotary folder cylinder parallel to said plate cylinders, rotary supplement cutter cylinders in operative relation to said folder cylinder and one set of said plate cylinders, angle bars and a former in operative relation to the other set or sets of plate cylinders; main cutter cylinders in operative relation to

5 said former and cutting independently of the folder cylinder and always cutting off a complete paper in book form—exclusive of supplement—for each revolution of the plate cylinders and folder rollers in operative relation to said main cutter cylinders, supplement cutter cylinders and first folder cylinder, as set forth.

10 5. In a multiple deck apparatus of the class described, the combination of multiple sets of rotary plate cylinders carrying plates with columns lengthwise of said plate cylinders; blanket cylinders coöperating with said plate cylinders; a rotary folder cylinder parallel to said plate cylinders; main cutter cylinders, supplement cutter cylinders and folder rollers in operative relation to said folder cylinder; a former in operative relation to said main cutter cylinders and one or more 15 sets of said plate cylinders and angle bars and a slitter-device in operative relation to said former and said plate cylinders, as set forth.

20 6. In a multiple deck apparatus of the class described, the combination of in multiple sets of plate cylinders carrying plates with columns lengthwise of said plate cylinders; blanket cylinders coöperating with said plate cylinders; a rotative folder cylinder parallel 25 to said plate cylinders; rotative supplement cutter cylinders in operative relation to said folder cylinder and one set of said plate cylinders; rotative first cutter cylinders in operative relation to said first folder cylinder; 30 a former, angle bars, and a slitter device in operative relation to said folder cylinder and said main cutter cylinders; first folder rollers in operative relation to said folder cylinder; a second folder device in operative relation 35 to said first folder rollers, means for conveying papers from said folder rollers to said second folder device and means for conveying papers from said second folder device; as set forth.

40 7. In an apparatus of the class described, the combination of half speed plate cylinders carrying plates with columns lengthwise of said plate cylinders, supplement cutter cylinders half the width of and in line with said half speed plate cylinders; a folder cylinder in operative relation to said supplement cutter cylinders; main cutter cylinders in operative relation to said folder cylinder and cutting independently thereof to cut off a complete paper in book form—exclusive of supplement—for each revolution of the plate cylinders and the cutter cylinders; angle bars and a former in operative relation to said main cutter cylinders; full speed plate cylinders in operative relation to said former and equipped 45 with exclusively original plates with columns lengthwise of the plate cylinders; and folder rollers in operative relation to said folder cylinder; all coöperating to take the supplement 50 from the half speed

50 plate cylinders and fold same between the sheets from the full speed plate cylinders, without bringing the supplement sheet into such position that it may be cut by the main cutter device. 70

55 8. In an apparatus of the class described, the combination of plate cylinders rotating at full speed and carrying plates with columns lengthwise of said plate cylinders; similar plate cylinders rotating at half speed; full 75 width angle bars for changing the direction of the webs from said full speed plate cylinders; a former; slitter devices between said former and said angle bars; a rotative folder cylinder; first cutter cylinders between said 80 former and said folder cylinder; supplement cutter cylinders between said folder cylinder and the half speed plate cylinders; and folder rollers coöperating with said folder cylinder, first cutter cylinders and supplement cutter 85 cylinders; as set forth.

9. The combination of revoluble printing couples plural plates wide, a revoluble folder-cylinder in width equal to the length of one page plus margins and parallel to said printing couples, main cutter devices adjacent to and cutting independently of said folder-cylinder to cut off sheets in length equal to the width of two pages plus margins for each revolution of the cutter cylinders and the plate 90 cylinders; angle bars receiving webs from said printing couples and leading same to a former, a former receiving webs from said angle bars and delivering said webs to said cutter devices, and folder rollers coöperating 95 with said folder-cylinder. 100

10. The combination of full-speed revoluble printing couples two plates in circumference and plural plates wide and equipped with exclusively original plates with columns lengthwise of the plate cylinders; half-speed printing couples one-plate wide two plates in circumference and equipped with original and duplicate plates, a revoluble folder cylinder one-plate wide and parallel to said printing couples, main cutter cylinders cutting independently of said folder cylinder, angle bars receiving webs from said full-speed printing couples, a former receiving webs from said angle bars and delivering said webs to said main cutter cylinder in longitudinal strips one plate wide with the pages of the webs respectively in registry, supplement cutter cylinders receiving one-plate-wide web from said half speed printing couples, and folder-rollers coöperating with 110 said folder cylinder. 115

11. The combination of revoluble printing couples two plates in circumference, plural plates wide and equipped with original plates exclusively, angle bars receiving webs from said printing couples and leading same to a former, a former plural plates wide in its large dimension and one plate wide in its smaller dimension and receiving and associat- 120 125 130

- ing the webs from said angle bars, a folder cylinder in width equal to the length of one page plus margins and parallel to said printing couples, cutter cylinders receiving webs from said former and cutting off independently of the folder-cylinder, sheets in length equal to the width of two pages plus margins for each revolution of the cutter cylinders, and folder rollers coöperating with said folder-cylinder and cutter cylinders.
12. The combination of full-speed printing couples two plates in circumference plural-plates wide and equipped with exclusively original plates with columns lengthwise of the plate cylinders, coöperating half speed printing couples plural-plates-wide, a folder cylinder one-plate-wide in line with said half-speed printing-couples, full-width angle bars receiving webs from said full-speed plate cylinders, a former plural-plates wide in its larger dimension and one-plate-wide in its smaller dimension receiving webs from said angle bars, a main cutter device coöperating with said folder cylinder and receiving webs from said former in strips one plate wide, and supplement cutter devices and folder rollers coöperating with said folder cylinder to produce a complete paper in book form with insert sheet, for each revolution of the printing couples.
13. The combination of full speed printing couples plural plates wide, half-speed printing couples one-plate-wide, angle bars receiving webs from said full-speed printing couples and adapted to lead all of the members of said web always in parallel and invariably toward the main cutter cylinders, a folder cylinder one-plate-wide in line with said half-speed printing couples, one-plate-wide main cutter cylinders adjacent to and cutting independently of said folder cylinder and adapted to cut the associated web members into sheets in length equal to the width of two pages plus margins, supplement cutter cylinders in line with the half-speed printing couples and situated to deliver the cut supplement sheets on the quarter of the folder cylinder turning towards and adjacent to the main cutter cylinder, and folder-rollers opposite to said supplement cutter cylinders.
14. The combination of revoluble half speed printing couples, a revoluble one-plate-wide folder cylinder in line with said half-speed printing couples, supplement cutter devices between said folder cylinder and said printing couples and situated to deliver half speed supplement sheets traveling in a straight line onto the adjacent quarter of the folder cylinder approaching and adjacent to the main cutter cylinders, main cutter cylinders adapted to cut associated web members into sheets in length equal to the width of two pages plus margins, means for supplying printed webs to said main cutter cylinders, said webs running in parallel and invariably toward the folder cylinder, and folder rollers coöperating with said folder cylinder, main cutter cylinders, and supplement cutter devices.
15. A multiple-deck apparatus for printing and folding papers, comprising plural decks of full speed printing couples equipped with plate cylinders plural-plates-wide and two plates in circumference, said plate cylinders having all original plates with columns lengthwise of the plate cylinders; one deck of half-speed printing couples one-plate-wide and two-plates in circumference and equipped with duplicate sets of plates with columns lengthwise of the plate cylinders; a folder cylinder one-plate-wide and four plates in circumference and in line with said half-speed plate cylinders; means for associating in book form all the members of a single full-speed web running invariably forward and always in parallel before being acted upon by the folder cylinder; means for consolidating all of the associated web-members from the full-speed plate cylinders; means for cutting the associated and consolidated web members into sheets two pages in length before being acted upon by the folder cylinder, one cut being made for each and every revolution of the cutter cylinders and plate cylinders; means for cutting the half speed web into sheets one page in length; means for associating said one-page sheets with the two-page sheets on the folder cylinder; and folder rollers co-acting with said folder cylinder to fold together said two-page sheets and one-page sheet, the run of all of the webs and of all of the sheets cut therefrom being a continuous straight run in contra-distinction to the run of a web member back upon itself, also in contra-distinction to the run of one member of a web crosswise to the other member of the same web.
16. The combination of revoluble printing couples plural-plates-wide and having plate cylinders two-plates in circumference with columns lengthwise of the plate cylinders, a revoluble folder cylinder parallel to said printing couples, main cutter devices adjacent to and cutting independently of the folder cylinder and adapted to cut sheets two pages in length for each revolution of the plate cylinders, angle bars, one for each deck, carrying full width webs from said printing couples, a former receiving plural-plates-wide webs from said angle bars and delivering the associated members of all of said webs to said cutter devices, and folder rollers coöperating with said folder cylinder.
17. In an apparatus for printing and folding papers, the combination of full-speed printing couples having plate cylinders plural plates wide and two plates in circumference with columns lengthwise of the plate cylinders and equipped with all original plates and operating on web plural plates

wide; half-speed printing couples having plate cylinders two plates in circumference and one plate wide equipped with original and duplicate plates operating on a supplement web one-plate-wide; and a former in operative relation to said full-speed plate cylinders and having its nose in line with one edge of the supplement web printed on the half-speed plate cylinders.

10 18. In an apparatus for printing and folding papers, the combination of full-speed printing couples equipped with exclusively original plates with columns lengthwise of the plate cylinders and arranged to invariably 15 produce an exclusively original page-for-plate product under all conditions of operation, supplement printing couples coöperating with the full-speed printing couples, means for slitting the webs printed on the 20 main printing couples, an associating device adapted to associate all of the members of the main webs during the continuous parallel run of all of said webs and web-members, a one-plate-wide folder cylinder coöperating 25 with the full-speed printing couples and the supplement printing couples, a revolute one-plate-wide main cutter device adapted to cut full-speed web-members into sheets in length equal to the width of two pages plus 30 margins for every revolution of the main printing couples and the main cutter device,

a one-plate-wide cutter device adapted to cut the supplement web into sheets in length equal to the width of one page plus margins during the continuous straight run of the 35 supplement web always in parallel with all of the members of the main webs, means for associating on the folder cylinder invariably in book form, all the sheets cut from the full-speed webs and the sheet cut from the 40 supplement web, the main sheets associated on the folder cylinder being invariably the same width as and always in line with the supplement sheet and always in width equal to the length of one page plus margins, and 45 means for folding together invariably in book form all of the associated main sheets and the supplement sheet, at the maximum rate of speed of the full-speed printing couples, the run of all the webs, all of the 50 web-members and of all the sheets cut from the webs and the web-members being invariably a continuous straight run, always in parallel, from start to finish.

In witness whereof I have hereunto signed 55 my name at Springfield Illinois this 17th day of September 1904.

JOHN A. BOYCE.
